UNITED STATES PATENT OFFICE

MILTON WILSON, OF OKLA, SASKATCHEWAN, CANADA

CONVEYER SLAT

Application filed September 24, 1928, Serial No. 307,863, and in Canada August 13, 1928.

The invention relates to improvements in conveyor slats and more particularly to a slat designed for use on binder conveyors or canvases and an object of the invention is to provide a slat arrangement which will materially prolong the life of the canvas and which positively prevents any possibility of grain, chaff, bugs and so forth getting between the slat and the canvas.

10 A further object is to provide a particularly strong slat construction and also a slat having carrier members at the ends thereof which reduce materially the wear on the edges of the canvas.

15 A further object is to construct the device in a simple manner and such that the canvas can be provided with the slats at reasonable cost.

With the above more important objects in view, the invention consists essentially in the arrangement and construction of parts hereinafter more particularly described, reference being had to the accompanying drawing, in which:—

25 Fig. 1 is a perspective view of a part of a binder canvas embodying my invention.

Fig. 2 is an enlarged detailed vertical sectional view at 2—2' Figure 1.

Fig. 3 is an enlarged detailed vertical sectional view centrally and longitudinally through one end of the slat and associated parts.

Fig. 4 is a vertical sectional view at 4—4' Figure 3.

35 Fig. 5 is a sectional view similar to Figure 4 of a modified construction.

In the drawing like characters of reference indicate corresponding parts in the several figures.

40 The conveyor or canvas 1 is of the usual type employed on binding machines and it is supplied at suitable intervals as is customary with cross slats to gather and carry the grain. According to my invention, the slats are all constructed as now described, reference being had initially to Figures 1 to 4 inclusive.

45 In carrying out the invention as shown in the latter figures, I provide a wooden cross slat 2 having a length approximately equal to the width of the canvas and a width as is

usual and provided on the under side with a plurality of spaced cross channels 3.

Over each of these strips I pass the canvas which goes up one side the strip, across the top thereof and down the other side as best shown in Figures 2 and 4. I provide also channel shaped metal strips 4 having a length approximately equal to the width of the canvas and which are adapted to be placed over those parts of the canvas covering the wooden strips 2. The metal strips have their edges extending downwardly below the sides of the wooden strip and formed so that they will in no way cut the canvas. In the present instance, I have shown the edges of the metal strips as rolled over wires 5 and 6.

55 The metal strips are longitudinally corrugated as indicated at 7 and this serves not only to reinforce the metal strips but also to cause them to better gather the grain. The metal strips are fastened to the wooden strips by relatively long rivets 8 which pass through the canvas and through the channels 3 hereinbefore mentioned. The canvases or conveyors of binding machines have their ends carried by supporting wood strips attached to the binder frame and as such is common practice and well known, the same are not herein shown.

60 In order to guard the edges of the canvas and protect the same from unnecessary wear by contact with such mentioned strips, I have provided carriers 9 on each end of the slat. These carriers are both identically constructed and each is in the form of a relatively short channel bar 10, the up turned flanges 11 and 12 of which pass between the sides of the wood strip 2 and the passing portions of the canvas strip and are held by the end rivet 8. A vertical rivet 13 passes also through the inner end of each carrier and upwardly through the slat, canvas and strip 4.

65 It will be observed that the base 14 of the carrier is contained in a lower horizontal plane than the outturned ends of the canvas so that when the canvas is in operating position within the binder frame, the carriers 9 will ride the carrying strips on the binder before mentioned and not herein shown and 100

will hold the canvas clear of the same thereby materially saving the edges of the canvas from wear.

It will be apparent from the above description that there is no possibility of grain, chaff, bugs or so forth getting underneath the slat as so commonly occurs with the type of slats now used and that the type of slat provided is particularly strong and durable and guards the canvas from rotting and pulling away from the slat as so commonly occurs at the present time.

In Figure 5, I have shown a modification of the invention and in this construction the wooden slat is entirely dispensed with and in its place I have substituted a longitudinally corrugated, channel shaped, inner strip 15. In this type of construction, the canvas is caught between the inner strip 15 and the outer strip and instead of employing a single relatively long end rivet 8 and a vertical rivet 13, I utilize two pairs of short rivets 16 and 17 to fasten the carrier in place.

What I claim as my invention is:—

The combination with a canvas conveyer, of a cross strip substantially rectangular in vertical cross section and over which the canvas is passed, a longitudinally corrugated channel-shaped strip overlying the canvas and having the side flanges thereof extending downwardly beyond the base of the former strip, means permanently fastening the side flanges of the outer strip to the inner strip, said means passing through the canvas and carrier members, underlying the ends of the inner strip and extending downwardly beyond the out passing ends of the canvas strip.

Signed at Winnipeg, this 8th day of September, 1928.
